UNITED STATES PATENT OFFICE.

FRANCIS ANDERSON, OF PORTADOWN, IRELAND.

DESIGN FOR A TEXTILE FABRIC.

Application filed January 23, 1926. Serial No. 16,247. Term of patent 14 years.

To all whom it may concern:

Be it known that I, FRANCIS ANDERSON, a subject of the King of Great Britain, residing at Portadown, county Armagh, Northern Ireland, have invented a new, original, and ornamental Design for Textile Fabric, of which the following is a specification, reference being had to the accompanying drawing, forming part thereof.

In the drawing, Fig. 1 is a view of one face of the fabric with the new design.

Fig. 2 shows the opposite face of the fabric.

I claim:

The ornamental design for textile fabric substantially as shown.

FRANCIS ANDERSON.
